TRAVELER MECHANISM

Boutwell H. Foster, Maplewood, N. J., assignor, by
mesne assignments, to United States Rubber
Company, New York, N. Y., a corporation of
New Jersey

Application August 7, 1934, Serial No. 738,800

6 Claims. (Cl. 118—59)

This invention relates to an improvement in spinning, twisting or covering machines of the ring type, and more particularly to an improvement in traveler mechanisms therefor.

5 In present day spinning, twisting and covering machines of the ring type, a common form of traveler mechanism comprises a ring mounted on the ring rail, the upper edge of the ring being provided with inwardly and outwardly projecting flanges to act as retaining means for the traveler. The traveler commonly used is of substantially C shape and is made of fine spring wire or metal strip. In use, the free ends of this traveler are sprung over the flanges of the ring
10 so as to loosely engage the ring beneath its flanges, and the thread or yarn passes down through the traveler and thence onto the bobbin disposed within the ring. As the bobbin rotates it exerts a pull on the thread which causes the traveler to be dragged around the ring.
15

This form of traveler is open to a number of objections, among which are the following. The traveler wears out with undesirable rapidity, which wear is hastened by increased friction
20 caused by centrifugal action. Also due to the manner in which it is dragged along by the thread or yarn, it does not move around the ring in a vertical position but is tilted, and this tilting not only causes a binding effect and increases the wear on the traveler, but it also makes the traveler chatter, thus preventing the yarn from running with the desired smoothness. Also, with this type of traveler, the tension on the thread or yarn as wound is not of the desired uniformity,
25 because when the bobbin is empty, the direction of the thread leaving the traveler is more at right angles to the path of the traveler and therefore at this time the friction between the thread and traveler is at a maximum and hence also the tension.
30 However, as the bobbin fills up the direction of the yarn leaving the traveler approaches more nearly the line of movement of the traveler, with a consequent decrease in friction and less tension on the thread. Further, by reason of the
35 friction at the traveler, small projecting portions of the fibers of the yarn or thread are scraped off, causing an accumulation of lint on the traveler and adjacent parts of the machine, and where the fibers in spinning or the yarns in
40 twisting are wet, this scraping off or linting is greater because of the tendency of the wet fibers to cling.
45

An object of the present invention is to provide an improved form of traveler having longer life, which enables the yarn to run more smoothly and with a more uniform tension, and which substantially reduces the amount of lint or accumulation of fiber on the machine parts.

50 Other objects will appear from the detailed description and drawing, in which latter—

Figure 1 is a plan view of the traveler mechanism;

Figure 2 is a vertical section through the mechanism on the line 2—2 of Fig. 1;

Figure 3 is a plan of the traveler per se; and 5

Figure 4 is a vertical section showing a slight modification.

Referring to the drawing, the numeral 1 designates generally the ring of the traveler mechanism, which comprises an outer ring member 2 which may be secured in any desired manner to the usual ring rail, as by providing a flange 3 which may be screwed to the ring rail 4. The top surface of the outer ring member may be provided with an oil groove 5 for a purpose to be later 10 described. Frictionally fitted in the outer ring member 2 is an inner ring member 6 at the upper end of which is a flange 7 which overhangs and is spaced from the outer ring member 2, the two ring members cooperating to provide a groove or 15 raceway 8, and in the form illustrated the desired height of raceway may be obtained by providing a small shoulder 9 at a desired height on the inner ring member, the engagement of which with the top of the outer ring member 2 limits 20 the downward movement of the inner ring member 6. The inner and outer ring members may be positively secured together, if desired, and in fact any equivalent construction of ring providing the desired raceway may be employed. 30

One form of the traveler per se is illustrated in plan in Fig. 3 and is preferably formed of an annulus or ring 10 of fine wire or narrow thin strip metal, in order that the weight of the traveler may be kept at a minimum. Attached to 35 the annulus 10 is a support 11 which is most clearly shown in Fig. 2 and which may be made of wire similar to the annulus 10. This support extends outwardly from the raceway and then upwardly and inwardly over the flange 7 to a 40 point within the circumference of ring 10, as most clearly shown in Fig. 2, and at its upper free end there is mounted a small grooved roller 12 which forms a guide for the thread or yarn and which may be made of aluminum or other 45 light material, in order to reduce the effect of centrifugal force. Also in order to compensate for the weight of the roller and its support, a counter-poise and bearing member 13 is mounted on the annulus 10 at a point about diametrically 50 opposite the roller. This counter-poise and bearing member can be of any suitable shape and material, and can conveniently be made from a small piece of small metal tubing which is slid over the wire composing the annulus 10 before 55 the ends of the wire have been united, and then permanently secured in position as by brazing or soldering. Or it may be made by rolling a small piece of sheet metal around the wire and securing it in place. The member 13, as before stated, 60

not only acts as a counter-poise but also functions as a bearing member to maintain the annulus 10 out of contact with the walls of the raceway 8 and thereby reduce friction. If desired, and preferably, additional smaller bearing members 14 may be disposed around the annulus 10, for instance at points spaced 90° apart.

The construction above described may be supplied as new equipment on a machine, and in Fig. 4 there is shown a slight modification capable of application to existing machines having the usual form of ring. In Fig. 4 the reference numeral 16 indicates the usual ring which in the present modification becomes the outer ring member. An inner ring member 17 is provided which is similar in its general construction to the ring member 6 and is provided with a shoulder 18 adapted to bear on the outer ring 16 and definitely limit the size of the raceway for the traveler. An oil groove 19 may also be provided in the upper surface of the outer ring member 16.

In operation the thread or yarn is led down under the grooved roller 12 of the traveler and thence onto the rotating bobbin 15 where it is wound up. It has been found that in use there is no tendency of the thread or yarn to escape from roller 12 under starting, stopping, and varied speed conditions. By the provision of the above described traveler mechanism, the undue friction, centrifugal action, uneven running and uneven tension inherent in the described former type of traveler are substantially obviated. The increased weight caused by the roller 12 would tend to increase centrifugal action and friction, but this is compensated for by the counter-poise 13 located diametrically opposite to the roller. Also, the members 13 and 14 provide bearings which prevent contact of the annulus 10 with the walls of the raceway at all times and thereby reduce friction. When the ring 10 is at rest it contacts with oil in the groove 5 and is thus lubricated. It has been found that in a period of extended use the wear on the traveler mechanism is negligible. Also, the more or less jerky dragging, or chattering, of the old C-shaped traveler is entirely obviated, with a consequent greatly improved smoothness in the running of the yarn. Since the small grooved roller 12 acts as the thread guide, the tension of the yarn when wound up is much more uniform because by reason of the rolling action, friction between the thread and its guide is substantially eliminated and hence the tension does not vary materially whether the bobbin is full or empty. Also, by reason of the reduction of the friction by the use of the roller 12, the linting of the thread is greatly reduced, and particularly when, as before stated, the fibers in spinning or yarns in twisting are wet. By extending inwardly the support 11 of roller 12, the leverage exerted by the thread on the ring 10 is reduced, and hence the tendency of the ring 10 to tilt is lessened.

The invention is generally applicable to machines of the ring type, whether used for spinning, twisting, or for covering cores such as elastic cores with a fibrous wrapping.

It is obvious that modifications can be made in the invention, and it is not desired to limit the same otherwise than is required by the prior art.

Having thus described my invention, what I claim and desire to protect by Letters Patent is:

1. A traveler mechanism for spinning, twisting or covering machines comprising a ring having an

external raceway, a traveler ring loosely disposed and rotatable in said raceway, a support carried by said last named ring and extending upwardly and inwardly thereof, a thread guide mounted on said support and comprising a small grooved roller, and a counterpoise and bearing member carried by said traveler ring at a point diametrically opposite said support.

2. A traveler mechanism for spinning, twisting or covering machines comprising a ring having an external raceway, a traveler ring loosely disposed and rotatable in said raceway, a support carried by said traveler ring and extending upwardly and inwardly thereof, a roller thread guide carried by the free end of said support, and a plurality of bearing members carried by said traveler ring at spaced intervals thereon.

3. A traveler mechanism for spinning, twisting or covering machines comprising an outer ring member, an inner ring member fitting therein and having at its top a flange overhanging and spaced above said outer ring member and forming therewith a raceway, a wire traveler ring loosely disposed and rotatable in said raceway, a support having one end secured to said traveler ring and its opposite end extending above and inwardly of said flange, a small grooved roller thread guide carried by said opposite end of said support, and a plurality of bearing members disposed at intervals on said traveler ring.

4. A traveler mechanism for spinning, twisting or covering machines comprising an outer ring member, an inner ring fitting therein and having at its top a flange overhanging and spaced above said outer ring member and forming therewith a raceway, means whereby said raceway may be lubricated, a tenuous traveler ring loosely disposed and rotatable in said raceway, a support secured at one end to said traveler ring and carrying at its opposite end a small roller thread guide, said roller being disposed above said flange and within the circumference of the traveler ring, and a plurality of bearing members disposed at intervals on said traveler ring and maintaining it out of contact with the walls of said raceway.

5. A traveler mechanism for spinning, twisting or covering machines comprising an outer ring member, an inner ring member fitting therein and having at its top a flange overhanging and spaced above said outer ring member and forming therewith a raceway, means whereby said raceway may be lubricated, a tenuous traveler ring loosely disposed and rotatable in said raceway, a support secured at one end to said traveler ring and carrying at its opposite end a small roller thread guide, said roller being disposed above said flange and within the circumference of the traveler ring, and a plurality of bearing members disposed at intervals on said traveler ring and maintaining it out of contact with the walls of said raceway, one of said bearing members being disposed diametrically opposite said roller guide and forming a counterpoise therefor.

6. A traveler mechanism for spinning, twisting or covering machines comprising a ring having an external raceway, a traveler ring loosely disposed and rotated in said raceway, a support carried by said traveler ring and extending upwardly and inwardly thereof, a thread guide carried by the free end of said support, and a plurality of bearing members carried by said traveler ring at spaced intervals thereon.
